UNITED STATES PATENT OFFICE.

EIÑO CASTRÉN AND EINARI OKSA, OF ENSO, SUOMI-FINLAND.

CONICAL WOOD-CHIP DISTRIBUTOR FOR CHEMICAL PULP BOILERS.

Application filed October 23, 1926, Serial No. 143,728, and in Suomi-Finland February 10, 1926.

There is a general endeavour to feed the chemical pulp boiler in such a way that the wood chips fed in, are distributed as evenly as possible on the whole transverse surface 5 of the boiler so as to avoid the chips accumulating in heaps, which eventually will break down forming air pockets resulting to an uneconomical utilization of the capacity of the boiler. For this end there are 10 different designs in use.

Our invention has for its object to accomplish the above requirement by means of a new device, which increases the efficiency of the pulp boiler by 25 to 30%.

15 On the accompanying drawing Fig. 1 shows the device in longitudinal section whereas Fig. 2 is a cross section of same.

When the chip jet has entered the boiler through the feed opening, it will at a distance of about 1 meter from the said opening 20 strike against a conical distributor 1, having for its object to change the direction of motion of the chips in such a way, that a portion of the chip mass is directed towards 25 the periphery of the cylindrical boiler. The cone 1 is supported by three pipes 2 attached to a larger annular pipe 3, which is supported by the intake flange of the boiler and thus carries the whole weight of the distributor. In order to cut down the time required 30 for feeding the boiler there is a vacuum created inside of same effecting the introduction of the chips at a considerable velocity. The vacuum is created in the known way 35 of letting steam condensate into an enclosed vessel. The charging of the boiler according to our invention takes place thus by letting steam first fill the boiler through a valve at the bottom of the boiler thus expelling the 40 air from same. Steam is hereafter introduced into the distributor through pipes 2 and 3, the wood chips being simultaneously fed in through a hopper 6, which is detachably mounted onto the distributor. The cold 45 chips thus cool off the steam, thus effecting condensation. The vacuum may be regu-

lated by the quantity of steam introduced through the pipe 3. If a very high vacuum is wanted this may be created by introducing cool cooking acid through the gas valve at 50 the upper inlet of the boiler, which may also be regulated at will. In order to get the steam well mixed with the chips, the former is, as mentioned, introduced through the pipes 2 and 3 into a manifold 4 in the lower 55 portion of the distributor 1, from which the steam is pressed out through an opening 5 formed by the mantle of the distributor 1 and the folded down rim of the manifold 4 thus mixing effectively with the chips sliding 60 down on the conical surface 1.

We claim:

1. A charge distributing apparatus for pulp boilers comprising a cone suspended at the inlet of a pulp boiler and in the path 65 of the charge, and means whereby a fluid pressure is admitted under the cone to more evenly distribute the charge inside the boiler.

2. A charge distributing apparatus for pulp boilers comprising a cone suspended at 70 the inlet of a pulp boiler, means whereby a steam pressure is admitted under the cone and adapted to disintegrate the charge at the same time creating a vacuum inside the boiler by condensation, said vacuum further 75 assisting the complete distribution of the charge in the boiler.

3. A charge distributing apparatus for pulp boilers comprising a fixed cone suspended at the inlet of a pulp boiler and in 80 the path of the charge, a plurality of pipes extending from under the cone to a position outside the boiler's inlet said pipes being adapted for connection to a steam supply and arranged to emit a steam charge beneath 85 the cone to facilitate the distribution of the said charge.

In witness whereof we have hereunto set our hands.

EIÑO CASTRÉN.
EINARI OKSA.
